(57) **CLAIM**

The ornamental design for a tent, as shown and described.

DESCRIPTION

FIG. 1 is a perspective view of a tent, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is an enlarged view of portion 9 circumscribed within FIG. 1;

FIG. 10 is an enlarged view of portion 10 circumscribed within FIG. 2; and,

FIG. 11 is an enlarged view of portion 11 circumscribed within FIG. 3.

The dot-dash broken lines depict the boundaries of the enlargements that form no part of the claimed design.

1 Claim, 11 Drawing Sheets
